UNITED STATES PATENT OFFICE.

JOHN A. PRICE, OF SCRANTON, PENNSYLVANIA.

COOKING STOVE OR RANGE.

SPECIFICATION forming part of Letters Patent No. 278,267, dated May 22, 1883.

Application filed December 15, 1882. (No model.)

To all whom it may concern:

Be it known that I, JOHN A. PRICE, of Scranton, in the county of Lackawanna and State of Pennsylvania, have invented certain new and useful Improvements in Ranges; and I do hereby declare the following to be a full, clear, and exact description of the same, reference being had to the accompanying drawings, forming part of this specification, and to the figures and letters of reference marked thereon.

This invention consists in certain novel improvements in ranges, which I will first describe, and then point out particularly in the claims at the end of this specification.

Referring to the accompanying drawings, Figure 1 represents a perspective view of a range provided with my improvements; Fig. 2, a longitudinal vertical section of the same; Fig. 3, a detail view of the shelf and range-back, showing the shelf turned down so as to present its narrowest supporting-surface; and Fig. 4 is a front view of the shelf and range-back.

Similar letters of reference in the several figures denote the same parts.

A represents the top of the range, having the openings 1 2 3 4, closed by removable covers, as usual. In ranges as ordinarily constructed the smoke and other volatile products of combustion are taken off either through a pipe leading from an opening in the top of the stove, near the rear thereof, and extending directly up into the chimney-flue, or through a pipe leading from an opening at the rear of the stove, below the top thereof; but in my present invention I locate the discharge-opening B of the range in the top of the range, near the rear thereof, and place over such discharge-opening a box or chamber, C, which extends backward behind the permanent back E of the range, as shown, and connects with a flue, D, adapted to discharge into the chimney-flue proper. My object in adopting this arrangement of flues and permanent back is two-fold, namely: First, the range is thereby adapted to fit into an ordinary fire-place, and to discharge the smoke, &c., direct up the chimney-flue without special adaptation of the latter, differing in this respect from those ranges in which the smoke-discharge is through an opening at the back of the stove, below the top surface

thereof, and which require a special construction of chimney-flue; and, secondly, by employing a permanent range-back, E, and discharging the smoke, &c., from the opening in the top of the range proper into the box or chamber C, and directing such smoke, &c., by the said box or chamber behind the permanent back and into the flue D, which leads up the chimney, I am enabled to connect a swinging shelf to the front of the permanent back, as will be hereinafter more fully described, my construction differing in this respect from those ranges which have a smoke-discharge opening in the top near the rear, with which is connected a pipe leading directly up the chimney-flue, for in such ranges no swinging shelf can be employed, because the smoke-pipe will interfere with its swinging motion.

To suitable lugs, k, on the front of the permanent range-back I hinged a shelf, K, such as above referred to. This shelf, when raised, is adapted to be supported by a swinging bracket, L, mounted on bearings on the range-back and capable of being swung out or in, as required. By preference I extend the shelf K so that it will project beyond or flush with the rear side of the range-back, and form upon or connect to it a plate, M, which, when the shelf is swung up, as represented in Fig. 2, serves as a backing thereto, as seen at m; but when said shelf is swung down it (said plate M) continues a supporting-shelf, though narrower than shelf K, an angle-piece, n, forming a backing to it.

It will be seen by this arrangement that a supporting-shelf of greater or less width can be provided above the range, as desired, for the purpose of keeping warm cooked dishes, plates, or other articles; also, that by reason of the shelf K being hinged to the front of the range-back its motion is not interfered with at all by the smoke pipe or flue, as would be the case were the latter located in front instead of behind the range-back. Where the narrow shelf M is employed I preferably cut it away at the rear, so as not to obstruct the flue D.

Although I show in the drawings the chamber C, provided at the top with a removable plate, F, and a swinging plate or shelf, and at the front with an opening closed by a hinged valve, H, opened by the expansion and con-

traction of a rod or tube, I, I do not make claim to any of such features herein, though I reserve the right to claim the same in a future application.

Having thus described my invention, I claim as new—

1. The combination, with the range having the smoke-discharge opening in its top, near the rear, the permanent range-back, and the box or chamber connecting the discharge-opening and directing the smoke, &c., to the flue behind the permanent range-back, of a hinged shelf hinged to the front of the permanent range-back, the whole arranged and operating substantially as described.
2. The combination, with the range-back,

of the pivoted shelves, arranged at substantially right angles to each other, and the supporting-bracket, substantially as described.

3. The combination, with a stove or range having a back plate extending up above its top, and a shelf projecting forward from said back plate over the top, of a flue extending rearwardly from a smoke-discharge opening in the top to a point behind the back plate, where it connects with a smoke-flue proper, substantially as described.

JOHN A. PRICE.
